CLAIM

I claim the ornamental design for an attachment for an inhaler, as shown and described.

DESCRIPTION

FIG. 1 perspective view

FIG. 2 front view, wherein the rear view of FIG. 2 is not part of the claimed invention.

FIG. 3 side view of FIG. 2; and,

FIG. 4 plan view of FIG. 2.

The broken line showing of the inhaler and the rear of portion of the attachment are for illustrative purposes only and forms no part of the claimed design.
